ATTORNEY.

UNITED STATES PATENT OFFICE.

HUGH B. HOUSTON, OF PHILADELPHIA, PENNSYLVANIA, ASSIGNOR TO
J. E. CALDWELL & CO., OF SAME PLACE.

DESIGN FOR A BADGE.

SPECIFICATION forming part of Design No. 21,243, dated December 15, 1891.

Application filed November 21, 1891. Serial No. 412,687. Term of patent 14 years.

To all whom it may concern:

Be it known that I, HUGH B. HOUSTON, a citizen of the United States, residing in the city and county of Philadelphia, State of Pennsylvania, have invented and produced a new and original Design for a Badge, of which the following is a specification, reference being had to the accompanying drawing, forming part thereof.

10 The leading feature of my design for a badge is a seal with a figure of a lady thereon and radiating beams with stars thereon.

15 In the drawing, A designates a seal on the rim of which is the title "Society of the Colonial Dames of America," which, however, constitutes no part of the design. Within the rim of the seal is the figure B of a lady in the dress of the colonial times of America. Ra-

diating from the seal are beams C, on the ends of some of which are stars D. Another star 20 is at the bottom of the seal, making thirteen stars in all, suggestive of the original colonies of America. At the top of the seal is an eagle E with an olive or laurel branch F in his talons.

25 The badge is suspended from a suitable ribbon, which, however, forms no part of the design.

I claim—

The design for a badge, as shown and described.

HUGH B. HOUSTON.
